MARKING DEVICE FOR MARKING THE OP-
POSITE SIDES OF SHOE UPPER BLANKS
SIMULTANEOUSLYSamuel Sussman, Haverhill, Mass., assignor to
T. J. Edwards Inc., Boston, Mass., a corpora-
tion of Massachusetts

Application September 14, 1932, Serial No. 633,108

6 Claims. (Cl. 101—298)

The present invention relates to marking devices which are used in the manufacture of shoes to provide a shoe part, usually an upper blank, with marks useful as guides in subsequent operations such, for instance, as decorative stitching, overlay locating and applying, and reinforce or underlay locating and applying.

There are at least two forms of stitching used in the shoe industry for decorative purposes. In the first form, known as fancy stitching, the stitches are inserted by a needle operating from and penetrating into the finished or grain face of the shoe part. In the second form, known as gimp stitching, a cord, or other filament, or narrow fabric, is secured to the finished or grain face of the shoe part by stitches which are inserted by a needle operating from and penetrating into the unfinished or flesh face of the shoe part. To locate the positions of the fancy stitching and the overlays, such as collars, stripings and appliques, the guide lines are marked on the finished or grain face of the shoe part. To locate the positions of the gimp stitching, the reinforces and the underlays, the guide lines are marked on the unfinished or flesh face of the shoe part.

Heretofore attempts have been made to provide the shoe part with guide lines upon its opposite faces so that the marked shoe part could be provided both with fancy and gimp stitchings, or a fancy stitch design correlated with a reinforce or an underlay, or a gimp stitch design correlated with a collar or other overlay. To provide the opposite faces of the shoe part with guide lines required two separate operations, in one of which the guide lines were marked upon the finished or grain face of the shoe part and in the other one of which the guide lines were marked upon the unfinished or flesh face of the shoe part. While these two operations were performed in the same marking device it was necessary to use two separate marking members, to remove the shoe part from the device after it had been marked by one marking member, to remove the marking member and replace it with the second marking member, to remove the shoe part and to reinsert it into the device in a position reversed from that it occupied during the first marking operation, in order for the shoe part to receive the marks of the second marking member. As the shoe part is thin and limp it was found practically impossible to relocate its edge against the gage of the marking device for the second marking operation exactly as it was located against the gage during the first marking

operation. In consequence the marks were inaccurately placed on the shoe part by the second marking member, resulting in a lack of correlation between the fancy stitching and the gimp stitching, or between the fancy stitching and the underlay, or between the gimp stitching and the overlay.

The principal object of the present invention is to produce a marking device by which the opposite faces of the shoe part may be provided with accurate, legible guide lines simultaneously.

To the accomplishment of this object, and such others as may appear hereinafter, the various features of the present invention consist in certain methods, devices, combinations and arrangements of parts hereinafter described and then pointed out broadly and in detail in the appended claims which possess advantages readily apparent to those skilled in the art.

The various features of the present invention will be readily understood from an inspection of the accompanying drawing, illustrating the best form of the invention at present known to the inventor, in which,

Figure 1 is a view in plan of the marking device;

Fig. 2 is a view in sectional elevation on the line 2—2, Fig. 1;

Fig. 3 is a detail view in underside plan of the marking pattern;

Fig. 4 is a detail view in plan of a marked shoe quarter, the grain face being exposed to view, and

Fig. 5 is a detail sectional elevation on the line 5—5, Fig. 1.

For the purposes of disclosure the various features of the present invention are illustrated herein as embodied in the improved Edwards Stitch Marker disclosed in the patent to Edwards, No. 1,796,686, March 17, 1931. Generally, the improved Edwards stitch marker is provided with a marking member which is transferred from a position where its marking edge is provided with a coat of ink to a position where the inked edge engages and marks one face of a shoe part supported by a gage removably mounted upon a bed. The marks made upon the shoe part by the marking member are used as guides in subsequent operations such, for instance, as fancy stitching, gimp stitching, overlay locating and applying, and reinforce or underlay locating and applying. To locate the positions of the fancy stitching and the overlays, such as collars, stripings and appliques, the guide lines are marked on the finished or grain face of the shoe part. To locate the positions of the gimp stitching, the

reinforces and the underlays, the guide lines are marked on the unfinished or flesh face of the shoe part. Heretofore, attempts have been made, through the use of the improved Edwards stitch marker, to mark the shoe part with guide lines upon its opposite faces so that the marked shoe part could be provided in subsequent operations both with fancy and gimp stitchings, or a fancy stitch design correlated with a reinforce or an underlay, or a gimp stitch design correlated with a collar or other overlay.

In preparing for these various markings by the improved Edwards stitch marker two marking members were made, one being provided with an edge for marking the finished or grain face of the shoe part, and the other being provided with an edge for marking the unfinished or flesh face of the shoe part. After the first marking member was inserted into the improved Edwards stitch marker it would be transferred from the ink pad to the finished or grain face of the shoe part supported on a gage of the bumper type carried by the bed. Then the first marking member was removed, replaced by the second marking member, and the shoe part turned over and its edge relocated against the gage. Then the second marking member was operated to ink the guide lines on the unfinished or flesh face of the shoe part.

This mode of operation proved impracticable as it was found practically impossible to relocate the edge of the thin, flimsy shoe part against the gage for the second marking operation exactly as said edge was located against the gage during the first marking operation. In consequence the second marking operation was performed inaccurately.

In order to place the marks accurately upon the opposite faces of the shoe part and thus be able to correlate the fancy stitching and the gimp stitching, or the fancy stitching and the underlay, or the gimp stitching and the overlay, the finished or grain faces 6 (Fig. 4) of the shoe parts 7, herein shown as a pair of quarters, are engaged with the transfer face 8 (Fig. 1) of a transfer sheet 9 which is supported, transfer face uppermost, upon the bed 10. Mounted on the bed 10, over the transfer sheet 9, is the removable pattern plate 11 provided with the cut-outs 12 and 13 which receive the thin and flimsy quarters 7. As shown in Fig. 1 certain portions of the walls of the cut-outs 12 and 13 act as guides to engage the edges of the quarters and locate them properly to receive upon their unfinished or flesh faces 14 the guide lines inked thereon by the marking member 15.

The marking member 15 (Fig. 3) is provided with two sets of marking edges, one set making the marks on one quarter and the other set making the marks on the other quarter. Each set is provided with two edges 16 and 17 for marking the gimp stitch guide lines 18 and 19 (Fig. 1) and with two edges 20 and 21 for marking the overlay locating and applying guide lines 22 and 23 (Fig. 4).

With this construction pressure of the marking edges against the unfinished or flesh faces of the supported quarters not only inks lines thereon but transfers from the transfer face of the transfer sheet identical lines to the finished or grain face of the supported quarters. Thus marking substance is deposited upon the opposite faces of the supported shoe parts simultaneously.

The guide lines 18 and 19 on the unfinished or

flesh face of the quarters are used as guides in the subsequent gimp stitching operation. In this operation the needle operates from and penetrates into the unfinished or flesh face of the quarter in inserting the stitches which pass over and secure to the finished or grain face of the quarter a narrow strip of fabric, cord or other filament. Thus, the lines on the finished or grain face of the quarter corresponding to the guide lines 18 and 19 on the opposite face are covered and hidden from view by the gimp stitching.

The lines 22 and 23 on the finished or grain face are used as guides in locating and attaching the stripings which are narrow bands having a width commensurate with the distance between adjacent marks 22 or 23 and a length corresponding to the lengths thereof. As the marks on the face 14 corresponding to the marks 22 and 23 are covered by the lining of the finished shoe they need not be removed.

By marking the opposite faces of the shoe part simultaneously the correlation of the gimp stitching and the stripings at their points of meeting (Fig. 4) on the finished or grain face of the shoe part is ensured.

The transfer sheet may extend from a supply roll 24 to a rewind roll 25. To this end the roll 24 is supported from brackets 26 (Fig. 1) projecting forwardly over the rear end of the pattern plate 11. To permit the unwinding of the transfer sheet, the roll receives at each end a head 27 (Fig. 5) provided with a collar 28 abutting the roll. The heads 27 are formed on one end of pins 29 which are loosely fitted into the brackets 26. To insure that the transfer sheet is unwound evenly from the roll 24 and to hold the roll 24 in position, coiled springs 30 are interposed between the brackets 26 and the collars 28, respectively. With this construction, the roll 24, although held securely in place, may be readily removed from the brackets 26 by pulling outwardly on the pins 29. As shown in Fig. 2, the transfer sheet upon being unwound from the roll 24 passes, coated or transfer face up, under a shaft 31 journaled in ears depending from the brackets 26. From under the shaft 31 the transfer sheet 9 passes along the surface of the bed 10 underneath the pattern plate 11 towards the front edge thereof. Here it is wound, coated or transfer face inward, upon a shaft 32 journaled in brackets 33 secured to the bed 10 adjacent its front corners. One end of the shaft 32 is provided with a turning wheel 34.

While for purposes of disclosure the marks formed upon the opposite sides of the shoe part are to be used as guide lines in the subsequent operations of gimp stitching and of stripping locating and applying, it will be apparent to those skilled in the art that other marks may be made for use as guide lines in other subsequent operations such as fancy stitching and collar, reinforce and underlay locating and applying. That is, instead of correlating the guide lines employed in gimp stitching and stripping locating and applying, the illustrated embodiment of the present invention may be used to correlate the guide lines used in gimp and fancy stitching, in gimp stitching and collar locating and applying, or in fancy stitching and reinforce or underlay locating and applying. It will be understood also that the finished or grain face must be engaged with the transfer face of the transfer sheet as the marking substance from the sheet may not be transferred to the unfinished or flesh face although this face

will take the ink marks made by the marking member.

Nothing herein explained is to be interpreted as limiting the invention in the scope of its application to use in connection with the particular apparatus or the particular mode of operation or both selected for purposes of illustration and explanation. While the particulars of construction herein set forth are well suited to one mechanical form of the invention, it is not limited to these details of construction, nor to the conjoint use of all its features, nor is it to be understood that these particulars are essential since they may be variously modified within the skill of the artisan without departing from the true scope of the actual invention, characterizing features of which are set forth in the following claims by the intentional use of generic terms and expressions inclusive of various modifications.

20 What is claimed as new, is:

1. In a marking device, the combination with a base member, a roll of transfer sheet material supported at one end of the base member, and means for drawing a length of said transfer sheet, transfer face uppermost, from the roll and across the base member in engagement therewith, said drawn length providing a support for a shoe part the finished or grain face of which engages the transfer face of said drawn length, of means for simultaneously providing the unfinished or flesh face of the shoe part with at least one continuous legible guide line and pressing against said transfer face that portion of the finished or grain face of the shoe part which lies beneath said guide line.
2. In a marking device, the combination with a base member, a roll of transfer sheet material supported at one end of the base member, means for drawing a length of said transfer sheet, transfer face uppermost, from the roll and across the base member in engagement therewith, and a guide pattern, superimposed on the transfer face of the drawn transfer sheet, provided with at least one opening for exposing said transfer face and for receiving a shoe part with its finished or grain face in engagement with said transfer face, of means for simultaneously providing the unfinished or flesh face of the received shoe part with at least one legible guide line and pressing against said transfer face that portion of the finished or grain face of the shoe part which lies beneath said guide line.
3. In a marking device, the combination with a base member, a roll of transfer sheet material supported at one end of the base member, means for drawing a length of said transfer sheet, transfer face uppermost, from the roll and across the base member in engagement therewith, and a guide pattern, superimposed on the transfer face of the drawn transfer sheet, provided with at least one

opening for exposing said transfer face and for receiving a shoe part with its finished or grain face in engagement with said transfer face, of means for simultaneously depositing marking substance to form at least one legible guide line on the unfinished or flesh face of the received shoe part and pressing against said transfer face that portion of the finished or grain face thereof which lies beneath said guide line.

4. In a marking device, the combination with 10 a base member provided with a planaform surface, a roll of transfer sheet material supported at one end of said surface, a shaft adjacent said surface, means for drawing a length of said transfer sheet, transfer face uppermost, from the roll, under said 15 shaft, and across said surface in engagement therewith, and a guide pattern, superimposed on the transfer face of the drawn transfer sheet between the shaft and the sheet drawing means, provided with at least one opening for exposing 20 said transfer face and for receiving a shoe part with its finished or grain face in engagement with said transfer face, of means for simultaneously providing the unfinished or flesh face of the received shoe part with legible guide lines and pressing 25 against said transfer face those portions of the finished or grain face of the shoe part which lie beneath said guide lines.

5. That improvement in the art of marking shoe parts which consists in supporting a transfer sheet with its transfer face uppermost, placing the shoe part upon the transfer sheet with its finished or grain face in contact with the transfer face of the transfer sheet, and engaging the unfinished or flesh face of the shoe part with an edge 30 bearing a marking substance whereby the unfinished or flesh face is provided with a legible guide line and the finished or grain face is provided with an identical legible guide line transferred from the transfer face of the transfer sheet 35 by the pressure exerted by the edge on the shoe part.

6. That improvement in the art of marking shoe parts which consists in supporting a transfer sheet with its transfer face uppermost, placing the shoe 40 part upon the transfer sheet with its finished or grain face in contact with the transfer face of the transfer sheet, and engaging the unfinished or flesh face of the shoe part with a continuous edge bearing a marking substance whereby the unfinished or flesh face is provided with a continuous, 45 legible guide line and the finished or grain face is provided with an identical continuous, legible guide line transferred thereto from the transfer face of the transfer sheet by the pressure exerted 50 by the edge on the unfinished or flesh face of the shoe part.

SAMUEL SUSSMAN.
